The ornamental design for an ear flap hat, as shown and described.

DESCRIPTION

FIG. 1 is a side elevational view of an ear flap hat showing my new design;

FIG. 2 is a top plan view thereof, the bottom is plain and unornamented;

FIG. 3 is a top plan view thereof with the ear flaps secured in an alternate portion;

FIG. 4 is a rear elevational view thereof with the ear flaps down, the broken away portion of the cord is for illustrative purposes;

FIG. 5 is a front elevational view thereof;

FIG. 6 is a rear perspective view thereof with the ear flaps in an alternate position;

FIG. 7 is a rear perspective view thereof with the ear flaps in an alternate position; and,

FIG. 8 is a rear elevational view of a second embodiment showing my new design, the difference being the rear, the top, bottom, and sides are essentially the same as the embodiment of FIG. 1.

FIG. 2

FIG. 3

FIG. 4

FIG. 5

FIG. 6**FIG. 7****FIG. 8**
